UNITED STATES PATENT OFFICE

165,882

BATHING SUIT

Mortimer Solomon, New York, N. Y.

Application July 13, 1951, Serial No. 15,852

Term of patent 7 years

(Cl. D3—17)

To all whom it may concern:

Be it known that I, Mortimer Solomon, a citizen of the United States of America, residing in New York, county of New York, and State of New York, have invented a new, original, and ornamental Design for a Bathing Suit, of which the following is a specification, reference being had to the accompanying drawing, forming part thereof, Fig. 1 is a front view of a bathing suit showing my new design.

Fig. 2 is a rear view thereof.

I claim:

The ornamental design for a bathing suit, substantially as shown.

MORTIMER SOLOMON.
